US00D744880S

(12) **United States Design Patent**
Smith et al.

(10) **Patent No.:** US D744,880 S
(45) **Date of Patent:** ** Dec. 8, 2015

(54) **SCIENTIFIC INSTRUMENT**

- (71) Applicant: **Molecular Devices, LLC**, Sunnyvale, CA (US)
- (72) Inventors: **Thomas L. Smith**, Campbell, CA (US); **Grischa Chandy**, Fremont, CA (US); **Nicholas F. Talesfore**, Los Gatos, CA (US); **Joseph McArdle**, Cupertino, CA (US)
- (73) Assignee: **Molecular Devices, LLC**, Sunnyvale, CA (US)

(**) Term: **14 Years**

(21) Appl. No.: **29/511,283**

(22) Filed: **Dec. 9, 2014**

(51) **LOC (10) Cl.** 10-04

(57) **CLAIM**

The ornamental design for a scientific instrument, as shown and described.

DESCRIPTION

FIG. 1 is a perspective view of the scientific instrument according to one embodiment of the invention;
FIG. 2 is another perspective view of the scientific instrument according to one embodiment of the invention;
FIG. 3 is another perspective view of the scientific instrument according to one embodiment of the invention;
FIG. 4 is a top view of the scientific instrument according to one embodiment of the invention;
FIG. 5 is a bottom view of the scientific instrument according to one embodiment of the invention;
FIG. 6 is a front view of the scientific instrument according to one embodiment of the invention;
FIG. 7 is a back view opposing the front view of FIG. 6 of the scientific instrument according to one embodiment of the invention; and,
FIG. 8 is a side view of the scientific instrument, the opposing side being a mirror image thereof, according to one embodiment of the invention.
The dashed lines in various figures are for illustrative purposes only and form no part of the claimed design.
